(57) CLAIM

The ornamental design for a jumpsuit, as shown and described.

DESCRIPTION

FIG. 1 is a perspective view of a jumpsuit showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dash-dash broken lines depict portions of the jumpsuit that form no part of the claimed design. The dash-dot-dash broken lines define the bounds of the claim and form no part of the claimed design. The contrast in shading in the drawings represents contour and does not represent surface ornamentation, color, or finish.
